UNITED STATES PATENT OFFICE.

KEITH CANAN, OF MARION, INDIANA.

WRENCH.

Application filed May 26, 1923. Serial No. 641,625.

To all whom it may concern:

Be it known that I, KEITH CANAN, a citizen of the United States, and a resident of Marion, in the county of Grant and State 5 of Indiana, have invented certain new and useful Improvements in Wrenches, of which the following is a specification.

This invention relates to an improvement in wrenches, and has for its object to provide a wrench which may be readily converted from a socket wrench to an ordinary or angle wrench without impairing the capacity of the wrench to exert a powerful turning or twisting strain on the work.

15 A further object is to provide a wrench of this character having jaw faces or work engaging means which so grip or engage the work as to be effective to impart a powerful twisted strain or torque thereto without 20 liability of slipping or marring or deflecting the work.

A still further object is to provide a device of this character having a handle or operating means adapted for convenient 25 and effective manipulation irrespective of whether the wrench is used as a socket wrench or angle wrench, the said operating means or handle having these capacities and at the same time being of such a nature as to 30 present no obstructions when the wrench is not in use or when it is used as an angle wrench but being of a compact nature and of a well balanced and simple construction.

35 A still further object is to provide a wrench of this character and having the foregoing advantages and which at the same time is of simple and durable construction, reliable in operation and easy and comparatively inexpensive to manufacture.

40 Other objects and advantages of the invention reside in certain novel features of the construction, combination and arrangement of parts which will be hereinafter more fully described and particularly pointed out in the appended claim, reference being had to the accompanying drawings forming part of this specification, and in which:

Figure 1 is a view in elevation, showing the preferred embodiment of the invention 50 in use as an angle wrench;

Figure 2 is a view thereof, partly in longitudinal section and partly in elevation, and showing the wrench in use as a socket wrench;

Figure 3 is a detail view in edge elevation 55 of the wrench head;

Figure 4 is a similar view in central longitudinal section;

Figure 5 is a fragmentary view of the wrench head, showing the same in transverse 60 section, the plane of the section of Figure 5 being at right angles to the plane of section of Figure 4;

Figures 6 and 7 are plan views illustrating 65 the action of the jaw faces with small and large nuts;

Figure 8 is a detail view of the handle in central longitudinal section; and

Figure 9 is a detail view in plan of the auxiliary operating lever. 70

Referring to the drawings wherein for the sake of illustration is shown the preferred embodiment of the invention, the numeral 10 designates generally the wrench head which as clearly shown in section in Fig-

ure 4 includes a body portion or stock 11 with which a fixed jaw 12 is integrally formed or otherwise suitably connected. Below the fixed jaw 12 the body portion 11 is formed with a longitudinally extending 80

opening or recess 13 and below and communicating with the recess 12 is a transverse opening or recess 14. A moving or sliding jaw 15 is provided and has integral-

ly formed therewith a bearing portion or slide 16 which is fitted for easy sliding movement in the opening 13 of the stem 11. The under face of the bearing portion or slide 16 has cut or formed therein teeth 17 which are operatively engaged by a worm 90

or screw 18 accommodated in the transverse opening 14. The worm or screw 18 is mounted on a bearing pin 20 extending through the opening 14 and through an axial opening of the screw 18 and journaled 95 in bearings 21 provided therefor in the stock 11 of the wrench. A plug 22 is threaded into a counterbore 23 formed in the stock 11 around one of the bearings 21 and en-

gages the pin 20 to prevent axial or end- 100

wise displacement of the pin 20. With this arrangement the jaw 15 may be readily and easily adjusted toward and away from the jaw 12 so as to adapt the wrench for use with work of various sizes.

As shown in the drawings the jaws 12 and 15 are provided or formed with specially constructed jaw faces. These jaw faces are of identical construction so that a common description will serve for both. They are designated generally at 25 and each is formed with a pair of flat, plane work engaging surfaces 26 arranged at each side of the jaw face and an intermediate or central V-shaped depression or groove 27. It is to be understood of course that the flat plane surfaces 26 of one jaw is directly opposed to the corresponding surfaces of the other jaw and so also as to the V-shaped grooves 27.

The wrench head 10 also includes a shank, designated generally at 30 and which is preferably integrally formed with the stock 11 although it may be otherwise suitably connected to this stock if found desirable. The front and back faces of this shank 30 are plane, flat and are parallel to each other but one of the end faces, designated at 31 is arranged vertically or perpendicularly that is parallel to the vertical axis of the wrench head whereas the opposite or other end face, indicated at 32, inclines with respect to the vertical axis and with respect to the end face 31. The inclination of the face 32 may be varied as found suitable and in the drawings it is shown as having an inclination of approximately $22\frac{1}{2}^\circ$. This relation and formation of the shank 30 and its end faces 31 and 32 has a very important function in the use of the wrench as will be hereinafter fully set out.

A handle, designated generally at 35 is provided and is hollow and is preferably of tubular form. At one end the handle is enlarged to provide a socket 36 having flat parallel front and back walls 37 engageable with the flat front and back or side faces of the shank 30 and having one vertical end wall 38 parallel to the longitudinal axis of the handle 35 and an inclined end wall 39 which bears an angular relation to the longitudinal axis of the handle as well as to the end wall 38.

The wrench head 10 is adapted to be assembled with the handle 35 in two ways accordingly as it is desired to use the wrench as a socket wrench or as an angle wrench. If it is desired to use the wrench as a socket wrench it is usually desirable to have the handle and the wrench head coaxial so that in assembling the wrench head and handle for use as a socket wrench, the shank 30 is introduced into the socket 36 with the vertical end face 31 of the wrench engaging the

vertical end wall 38 of the socket and with the inclined end face 32 of the shank 30 of the wrench head engaging the inclined end wall 39 of the socket 36. On the other hand when it is desired to use the wrench as an angle wrench it may be considered desirable to have the handle 35 bear an angular relation to the wrench head 10 and this relation or arrangement may be readily accomplished by inserting the shank 30 of the wrench head in the socket 35 in such manner that the end face 31 of the shank engages the end wall 39 of the socket and that the end face 32 of the shank engages the end wall 38 of the socket. In other words if it is desired to change the relation of the wrench head to the handle from that shown in Figure 2 to that shown in Figure 1 the wrench head is withdrawn from the socket with the parts positioned as shown in Figure 2 and is rotated about its vertical axis through 180° . It is then reinserted into the socket to provide the arrangement of parts shown in Figure 1.

In either arrangement the wrench head is held in assembly with the handle by means of a locking pin 40 which is entered through the opening 41 provided in one wall of the socket 36 and extended through an opening 42 provided in the shank 30. As shown in the drawings one end of the pin 40 is headed, as at 43, and the opposite end is provided with a reduced and threaded extension 44 which in the assembly engages a threaded opening 45 provided in the wall of the socket opposite the opening 41. This pin 40 is readily releasable so as to permit of adjustments and operations hereinabove described.

When the wrench is in use as a socket wrench it will usually be found desirable if not necessary to have an auxiliary operating lever in addition to the handle 35 and for this purpose an auxiliary operating lever 50 is provided and when not in use is housed in the hollow handle 35. In order to releasably hold the auxiliary operating lever 50 in the hollow handle 35 it is provided adjacent one end with an externally threaded annular shoulder 51 engageable with an internally threaded counterbore 52 provided in the lower end of the handle. Adjacent the shoulder 51 a knurled head 52 is formed on the operating lever 50 and facilitates placing of the lever in the handle 35 and the removal of the lever therefrom. At a suitable point in the handle 35 a number of pairs of bearing openings 55 are provided. It is to be understood of course that the members of each pair of bearing openings 55 are diametrically opposite. When the auxiliary operating lever is inserted in any pair of openings 55 as for instance as shown in Figure 2 the lever may be utilized for

conveniently applying a powerful twisting strain to the wrench head and consequently with the work with which it is engaged.

I claim:

- 5 In a wrench, a wrench head having a shank provided with a vertical face and an inclined face and a handle having a socket provided with a vertical wall and an inclined wall, the shank being adapted to be
10 fitted in the socket with its vertical face en-
- gaged with the vertical wall of the socket and with its inclined face engaged with the inclined wall of the socket or with its vertical face engaged with the inclined wall of the socket and with its inclined face en- 15 gaged with the vertical wall of the socket, and means for releasably securing the shank in the socket.

KEITH CANAN.
